UNITED STATES PATENT OFFICE.

PAUL LUX, OF WATERBURY, CONNECTICUT, ASSIGNOR TO THE WATERBURY CLOCK CO., OF WATERBURY, CONNECTICUT, A CORPORATION.

ALARM-CLOCK.

No. 866,873.

Specification of Letters Patent.

Patented Sept. 24, 1907.

Application filed July 1, 1907. Serial No. 381,663

To all whom it may concern:

Be it known that I, PAUL LUX, a citizen of the United States, residing at Waterbury, in the county of New Haven and State of Connecticut, have invented 5 a new and useful Improvement in Alarm-Clocks; and I do hereby declare the following, when taken in connection with the accompanying drawings and the letters of reference marked thereon, to be a full, clear, and exact description of the same, and which said 10 drawings constitute part of this specification, and represent, in—

Figure 1 a plan view of a clock-movement provided with my improved alarm-mechanism, the back cap of the case and the bell being also shown. Fig. 2 a 15 view through the movement in vertical section showing parts of the alarm mechanism. Fig. 3 a detached plan view of the pivotal switch. Fig. 4 a detached view of the verge-arbor with the switch-plate removed. Fig. 5 another view of the verge arbor showing the 20 switch-plate applied thereto. Fig. 6 a detached view of the switch-plate.

My invention relates to an improvement in that class of alarm-clocks in which provision is made for readily converting the clock from a long or continuous-alarm clock to an intermittent or spasmodic alarm clock, the object being to accomplish this end 25 by a mechanism of extreme simplicity, small cost and little liability to derangement.

With these ends in view, my invention consists in 30 a convertible alarm-mechanism for alarm-clocks, the said mechanism having certain details of construction and combinations of parts as will be hereinafter described and pointed out in the claims.

In carrying out my invention I employ a part 2 35 which for want of a better term I shall call a "converting switch" for the reason that its function is to convert the clock from a continuous to a spasmodic alarm and vice versa. This switch is secured by a pivot 3 to the outer end of a switch-plate or carrier 4 secured 40 by two rivets 5 to the forward end of a verge arbor 6 which is milled to form a flat face or seat 7 for the said plate 4 to bear upon. A stop-pin 8 mounted in the inner end of the said plate passes through a slot 9 in the switch and limits the swinging movement 45 thereof. The said plate 4 is formed with a hole 10 for the pivot 3, with two holes 11 for the rivets 5 and with a hole 12 for the stop-pin 8. The verge-arbor 6 is formed with two holes 6^a for the reception of the rivets 5. Under this construction the switch is car-

ried by and oscillates with the verge-arbor 6 which is 50 provided in the usual manner with a verge 13 and a hammer tail 14 carrying a hammer 15 arranged in position to strike the concentrically arranged bell 16 though obviously my invention is not confined to use in that class of clocks in which the bell is concentrically arranged at the back thereof. The said switch 2 is provided with a spasmodic-alarm arm 17 formed at its outer end with a forwardly turned finger 18 which coacts with a cam-wheel 19 mounted upon the arbor 20 of the 3rd wheel of the time-train which drives the 60 said arm. The switch 2 is also provided with an operating lever or finger 21 bent, as shown, to extend rearwardly through the back-cap 22 of the clock-case (not shown) and through the bell 16 which is formed with a slot 23 to give it passage. 65

When the lever 21 is thrown in one direction the switch 2 is swung on the pivot 3 and the finger 18 of the arm 17 brought into operative relations with the teeth of the cam-wheel 9 which is revolved by the time-train and secures an intermittent or spasmodic 70 sounding of the alarm as the high points of the teeth prevent the vibration of the lever 17 which is free to vibrate through its full sweep only when the finger 18 can vibrate between the teeth of the cam-wheel. As long, therefore, as the switch 2 is set for the coaction 75 of the finger 18 of the lever 17 with the teeth of the cam wheel 19, the clock will sound a spasmodic alarm. On the other hand, when the lever 21 is moved in the opposite direction, the finger 18 of the lever 17 is swung back as shown by broken lines in 80 Fig. 1 away from the cam-wheel 19 which is thus virtually cut out of action leaving the lever 17 free to vibrate through its full sweep until the alarm spring runs down, whereby the clock is converted into a long or continuous alarm. 85

All that is necessary to convert the clock from an alarm of one kind to the other is to swing the lever 21 very slightly. The let-off mechanism may be of any approved construction and is so well known as not to require detailed illustration or description. It 90 is sufficient to say that it comprises a let-off spring 24 coacting with the alarm-wheel 25 on the alarm-set arbor 26 and also coacting with the let-off wire 27 carried by the verge-arbor 6.

I claim:—

1. In a convertible alarm-mechanism, the combination with a vibrating arbor, of a pivotal switch mounted thereupon so as to vibrate therewith, a wheel driven by

95

the time-train and located in position to periodically interrupt the vibrations of the said switch when the same is pivotally swung into position for coaction with it, the pivotal movement of the switch being in a plane at a right angle to the plane of the wheel.

2. In a convertible alarm mechanism, the combination with a verge-arbor, of a carrier mounted thereupon, a switch pivotally mounted upon the said carrier and comprising a spasmodic-alarm arm and an operating lever, 10 and a wheel driven by the time-train and located in position to coact with the spasmodic-alarm arm of the

said switch when the same is pivotally swung into position for coaction with the said arm, the pivotal movement of the switch being in a plane at a right angle to the plane of the wheel.

In testimony whereof, I have signed this specification in the presence of two subscribing witnesses.

PAUL LUX.
